FIG.6

FIG.7

FIG.8

FIGS. 1 and 2 are rear and front perspective views of a checkout counter embodying my new design, respectively;

FIGS. 3 and 4 are fragmentary elevational views taken from the left and right sides thereof, respectively;

FIGS. 5 and 6 are rear and front perspective views of a modified form of the checkout counter shown in FIG. 1, respectively; and

FIGS. 7 and 8 are fragmentary elevational views taken from the left and right sides of the modified form shown in FIG. 5, respectively.

The change return tray is omitted from FIGS. 4 and 8 for convenience of illustration only.

The dominant features of my design reside in the full-line portions of the drawings.

This application is a continuation application of my co-

pending applications, Serial Nos. D. 63,527 and D. 63,529, both filed January 11, 1961, now abandoned.

I claim:

The ornamental design for a checkout counter, as shown and described.
